UNITED STATES PATENT OFFICE.

FRED O. C. BROWN, OF GRAND RAPIDS, MICHIGAN.

SHOESTRING-FASTENER.

1,071,696.

Specification of Letters Patent.

Patented Sept. 2, 1913.

Application filed March 14, 1911. Serial No. 614,389.

To all whom it may concern:

Be it known that I, FRED O. C. BROWN, a citizen of the United States, residing at Grand Rapids, in the county of Kent and State of Michigan, have invented a new and useful Shoestring-Fastener, of which the following is a specification.

This invention relates to cord holders, and more especially to those devices which 10 are adapted to embrace a knot in a lacing terminal; and the object of the same is to greatly simplify a cord holder of this character so that it may be employed on a laced shoe and in connection with the ordinary 15 flat or round shoestring by tying a hard knot in the latter.

An additional object is to prevent the string from becoming accidentally untied.

These objects are accomplished by the 20 construction hereinafter more fully described and claimed, and as shown in the drawings wherein—

Figure 1 is a perspective view of the upper portion of a laced shoe provided with 25 my invention. Fig. 2 is a horizontal section through the same on the line 2—2 of Fig. 1. Fig. 3 is a plan view of the hook, and Fig. 4 is a central vertical section thereof, both being on an enlarged scale.

30 In the drawings, the letter S designates a shoe open down its front as usual, and at either side thereof there are hooks H for the reception of the lacing strings L as shown in dotted lines.

35 After lacing the shoe, it is customary to tie the ends of the string in a bow knot, and it is the object of the present invention to do away with this labor.

It is quite possible to make use of one 40 of the ordinary hooks H shown in Fig. 1, although by preference my device consists of hooks made a little larger as shown in that view, and one is secured at the upper edge of each side of the opening in the 45 shoe. Referring now to Figs. 3 and 4, the hook consists of a tubular body 5 provided with slits 6 in its lower end so that it may be upset or eyeleted as seen at 7 in Fig. 2, a flat flange 8 which lies against the outer 50 face of the leather of the shoe around the completed eyelet, and a hook consisting of a bill 9 which is formed initially as seen at 90 in Fig. 1 and which therefore curves upward and inward over the open upper end 55 of the eyelet and is convexo-concavo as best seen in Fig. 4 directly over the eyelet, its

cavity 10 standing by preference directly above the eyelet. The shank of the bill is rounded laterally as indicated by the dotted line 11 in Fig. 3 so that the lacing may 60 pass through the same with as little wear thereon as possible, this being the ordinary construction given to lacing hooks on the market. Through the bill of the hook along its transverse center I then form a slot 12 65 best seen in Fig. 3, and this slot is continued around the bend of the hook as indicated at 13 in Fig. 4. In width the slot is slightly greater than the width of the ordinary lacing L, and its throat is disposed 70 at such point within the shank of the hook that the latter may be used for passing the string around the hook as usual and tying a bow knot in its ends. However, with my improved construction it is the intention 75 that the ends of the lacing string shall be led through the slot between the twin prongs 14 of which the hook is composed, and as indicated in dotted lines in Fig. 1.

In the use of a shoe having string fasteners of this character, the wearer puts on the shoe and laces it up and then draws the terminals of the string or lace through the slots 12 between the prongs 14 of the uppermost hooks, and then ties knots 20 in the 80 string ends as shown in Figs. 1 and 4. Thereafter having laced his shoe, he will pull the terminals a little tighter than necessary, draw the string through the slots 12 in the upper hooks, then press the string 85 ends toward the shoe, and then allow the tension to draw them inward so that the knots 20 pass under the tips 15 of the prongs 14 and come to rest as indicated in dotted lines in Fig. 4 partially within the eyelet 90 to retain the knot in position.

It will be observed that I do away entirely with any member upon the shoestring, and hence the strings in common use may be employed. Also it will be observed 100 that I form my shoestring fastener from one of the ordinary hooks now in common use, (although by preference I may make it a little larger than usual) and hence the manufacturer need go to no great expense 105 to provide a shoe with this device. Yet further it is clear that if the wearer does not care to use this form of fastener, he may use the hook in the customary way and tie the ends of the lacing to each other. But 110 from a mechanical standpoint, the advantage of this construction lies in the fact that

the cavity 10 beneath the prongs 14 stands directly over the eyelet through the body 5 so that the knot 20 drops partly into said eyelet and is thoroughly covered by the 5 twin prongs 14, and hence this device offers no unusual obstruction upon the outer surface of the shoe.

What is claimed is:

In a device of the class described, a plate 16 having an opening and a depending tubular eyelet surrounding the opening, one end of the plate projecting beyond the eyelet to form a flange and the other end of the plate being curved to form a hook overhanging 15 the eyelet, the extremity of the hook being disposed above the flange, the under surface of the hook being concaved directly above the eyelet, the hook being bifurcated to

form arms, the adjacent edges of which are parallel and extend entirely across the 20 mouth of the eyelet to a point between the inner and the outer edges of the flange, the flange constituting a means for directing a projection in a string between the parallel edges of the arms, and the parallel edges 25 of the arms constituting means for holding the projection in the concavity and in the mouth of the eyelet.

In testimony that I claim the foregoing as my own, I have hereto affixed my signature in the presence of two witnesses.

FRED O. C. BROWN.
